UNITED STATES PATENT OFFICE.

HARRY A. KUHN, OF PITTSBURGH, PENNSYLVANIA.

DISRUPTING DEVICE FOR MINING MACHINES.

1,320,872.

Specification of Letters Patent.

Patented Nov. 4, 1919.

Application filed May 18, 1914. Serial No. 839,335.

To all whom it may concern:

Be it known that I, HARRY A. KUHN, a citizen of the United States, and resident of Pittsburgh, in the county of Allegheny and State of Pennsylvania, have invented a new and useful Improvement in Disrupting Devices for Mining-Machines; and I do hereby declare the following to be a full, clear, and exact description thereof.

10 My invention relates to a device for disrupting or loosening coal in its bed after it has been expanded along its lines of cleavage, and is particularly adaptable for use in connection with a method of mining coal, 15 set forth and claimed in an application for Letters Patent of the United States filed by me October 21, 1913, Serial No. 796,497. In that application the method therein set forth involves the making of a kerf in a 20 solid wall of coal, shooting the coal so as to separate it along its lines of cleavage, and then undermining and conveying away the coal.

The present invention relates to a device 25 to be attached to the conveyer chain such as is employed in connection with the machine for carrying out the above described method, said chain being provided with a number of flights carrying cutters and moving over a 30 pan by means of which the coal is conveyed by the flights back to the mine-car in the rear. The device of the present invention consists of a shoe which is attached to the flights, and which is adapted to pass while 35 traveling over said pan into the mass of coal which has been separated along its lines of cleavage and which is adapted to disrupt the coal and destroy its adhesions, so that it is separated into lumps to be carried off by 40 the conveying mechanism.

In the accompanying drawings, Figure 1 is a plan view of a machine, such as above described, with my invention applied thereto; Fig. 2 is an enlarged view of a portion 45 of the chain and chain frame with my invention connected thereto; and Fig. 3 is an enlarged view showing the effect of the shoe in passing through the coal.

In Fig. 1, I have illustrated a plan view 50 of a machine for dislodging and conveying away coal and it comprises the frame 1 which is mounted on traction wheels 2 which are driven by suitable mechanism and by means of which the frame is advanced into 55 the coal. As my invention only relates to the shoe for loosening or disrupting the coal,

it will not be necessary for me to describe the details of the machine except that pertaining to the endless chain 3 which passes around the chain-frame 4 and around a rear 60 sprocket-wheel 5 and the front sprocket-wheels 6. The chain is adapted to be driven by suitable connections from a suitable motor 7.

Arranged at intervals on the chain 3 are 65 the flights 8 which are adapted to move over the pan 9 and act to convey the coal along said pan to the pit-car which is arranged in the rear of the machine. The flights 8 have the arms 8^a bearing against the chain frame 70 thereby relieving the thrust on the flights, all as set forth and claimed in an application filed by me of even date herewith, Serial No. 839,336.

Some of the flights 8 are provided with 75 cutters 10 and others are provided with the shoe 11. This shoe 11 is formed of steel or other suitable material, and has the inclined front portion 12. The shoe is connected to the flight arm by the bolts 13, and said bolts pass through the slots 14 in said flights so that the shoe may be adjusted at different positions on said flights. As shown in the drawing, I prefer to stagger these shoes on the flights different distances from 85 the outer ends thereof, as indicated in Fig. 1, so that they will act on different portions of the coal bed in passing through.

When the coal has been undercut and separated along its lines of cleavage by shooting, the coal will settle down into the undercut and as the flights pass into the coal as the machine is fed forward, the shoes 11 will burrow into the coal and will lift it in the manner indicated in Fig. 3, the coal 95 dropping back again as the shoe passes to be picked up by the succeeding flights and carried along the pan 9 to the rear of the machine. The shoes being arranged on flights at intervals from each other, this 100 raising and lowering effect on the coal due to the burrowing of the shoes therein, while supported by said pan, will give a kind of undulating effect to the coal and act to destroy the adhesions and separate the coal 105 into lumps to be carried away by the conveyer. The shoe follows in the path of the preceding flights and enters the space made thereby which permits the toe of the shoe to enter, the body of said shoe distorting the 110 adjacent coal as it passes through and releasing adhesions between lumps.

What I claim is:

1. In a device of the character described, the combination of a pan, an endless chain operating over said pan, a flight secured to said chain, a shoe secured to said flight arranged to re-act against the floor of said pan, and to project a lifting force as it rests on said floor of said pan.
- 5 2. In a device of the character described, the combination of a frame, a pan on the outer edge of said frame, an endless chain arranged to operate around said frame and
- 10

Copies of this patent may be obtained for five cents each, by addressing the "Commissioner of Patents, Washington, D. C."

over said pan, a flight carried by said chain and projecting outwardly in one direction, a shoe carried by said flight, said shoe being 15 beveled on its forward end and arranged to project beyond the forward edge of said flight.

In testimony whereof I the said HARRY A. KUHN, have hereunto set my hand.

HARRY A. KUHN.
